UNITED STATES PATENT OFFICE.

HORACIO MIRA, OF BOSTON, MASSACHUSETTS.

DENTAL CASTING-MACHINE.

1,283,859.

Specification of Letters Patent.

Patented Nov. 5, 1918.

Application filed September 6, 1917. Serial No. 190,064.

To all whom it may concern:

Be it known that I, HORACIO MIRA, a citizen of the Republic of Chile, residing at Boston, county of Suffolk, Commonwealth 5 of Massachusetts, have invented certain new and useful Improvements in Dental Casting-Machines, of which the following is a specification.

This invention relates to casting apparatus, and particularly to apparatus for making inlay castings for fillings and the like.

The object of my invention, broadly stated, is to improve and simplify existing apparatus of this class, particularly in respect to the instrumentalities for fusing the inlay and for forcing it into the mold.

According to my invention, the casting is fused in the depression made in the top 20 of the plaster of Paris or other investment by means of an electric arc, the movable element of which is brought into effective relation to the casting, and afterward automatically swung out of the way to permit a compressed air nozzle to be placed over the mold and the gold forced down into the cavity, the arrangement being such that the movement of the nozzle to its position over the mold automatically causes the movable 25 arc element to swing out of the way, thus permitting manipulation of both instrumentalities by one hand and obviating the necessity of handling the intensely heated electric arc.

Another feature of my invention consists 35 in the arrangement for automatically opening and closing the valve controlling the discharge of the compressed air into the mold, according to the position of the delivery nozzle with relation to the mold, whereby 40 the operative is relieved of the necessity of manually manipulating any control for the compressed air source.

A further feature of my invention consists 45 in the arrangement for adjusting the effective length of the arc, whereby the intensity of the heat application may be varied according to the requirements of the particular inlay being cast.

These and various other features which 50 will appear more fully hereinafter are secured in the device of the present invention. The construction and operation of which together with a preferred embodiment thereof 55 are disclosed in the following specification, illustrated in the accompanying drawings,

and particularly defined in the appended claims. Throughout the specification and drawings like reference characters are correspondingly employed and in the drawings: 60

Figure 1 is an end elevation, partially in section, of a dental inlay casting machine in accordance with my invention,

Figs. 2 and 3 are side views thereof, partially in section, showing the successive operative positions of the arc and nozzle, respectively, and

Figs. 4 and 5 are respectively a fragmentary plan view and a sectional elevation of the latching mount for the arc arm. 70

I have indicated at A a suitable base in which may be contained a source of compressed air B and upon which is mounted the mold C, the movable element D of the electric arc and the delivery nozzle E for 75 the compressed air.

The compressed air source may be of any desired type and is here shown only diagrammatically. The delivery nozzle E is connected with said source by any suitable 80 flexible connection, as the pipe 6. This nozzle includes a stem 7 having an axial bore 8 into the upper end of which the pipe 6 delivers. The lower end of the bore 8 is forked as indicated at 9, the ends of the 85 forks opening against the internal face of a sleeve 11 within which the stem 7 is slideable against the action of a spring 7¹ confined between said sleeve and a shoulder 7² formed on said stem. The bore 8 is normally 90 sealed by a conical valve 10 fixed to the lower end of the stem 7 and adapted to normally seat against a conical seat formed on the internal face of the sleeve 11. (See Fig. 3). Fast to the sleeve 11 is a suitably 95 flanged head 12 which may be provided with a facing of asbestos or other heat insulating material 13 and which is adapted to be brought into sealing relation with the plaster of Paris or other investment 48 of 100 the mold C. The head 12 and facing 13 are perforated as indicated at 12¹ to permit the passage of the compressed air from the bore 8 into the mold cavity when said bore is open. When the head 12 is brought down 105

against the mold, the stem 7 moves relative to the sleeve 11, compressing the spring 7¹, and carrying the valve 10 away from its seat, thus opening the bore 8; when the stem 7 is raised, the spring 7¹ holds down the head 110 12 until the valve 10 again finds its seat, thus closing the bore 8 whereupon the stem

7 and head 12 move together in the further lifting of the stem.

To effect this automatic opening and closing of the valve 10, the upper end of the stem 7 is pinned at 15 to a frame 16, provided with a handle 17, and pivotally mounted at 18 to a tubular upright 19 rising from the base A. The frame 16 adjacent its pivot 18 is notched as indicated at 20 to receive a latch rod 21 which is slidably mounted in the tubular support 19 rising from the cover plate of the base A. The rod 21 extends through said cover plate and there engages one end of a latch release lever 22, pivoted at 23 to the under face of said cover plate. The opposite end of the lever 22 engages a slidable latch rod 24 extending through said cover plate parallel to the rod 21 and guided in a suitable upright 25 rising from said cover plate. The upper end of the rod 24 works against the under face of a dog 26 which is pivoted at 27 to a boss 28 formed on arm 34 pivoted to a support 29 fastened to the cover plate of the base A, and suitably insulated therefrom as indicated at 30, the upper end of said support 29 being formed with a locking notch 31 adapted to be engaged by the under face of the dog 26. The boss 28 is chambered to receive a coil spring 32 confined therein about a pintle 33 set through the support 29. Mounted to turn on the pintle 33 is a suitably curved tiltable arm 34, the upper end of which is formed as a tubular holder 35 for the slidable sleeve 36 of the movable element of the electric arc arm 34, the support 29 being provided with a rigid extension 37 disposed under the tilting arm 34 and formed to support said arm 34 when said arm is in its non-effective position. (See Fig. 2).

The sleeve 36 is adapted to be adjusted longitudinally of the holder 35 to vary the intensity of the heat application. As here shown, the usual carbon element indicated at 36¹ is clamped within the sleeve 36 by a clamp 38 adjustably held to the sleeve by a collar 39 and set screw 40, the inner end of said element being received in a screw 50 stem 41 threaded through the rear end of the sleeve 36, the stem 41 with clamp 38, collar 39, and set screw 40 permitting the movable element 36¹ to be adjusted independently of the adjustment of the sleeve 36 and also providing for the removal of the element 36¹ for purposes of renewal.

The adjustment of the sleeve 36 may be effected in any desired manner. As here shown, one face of the sleeve is provided with a longitudinal series of rack teeth 42 with which meshes a pinion 43 mounted on a transverse shaft 44 disposed over the sleeve and provided with an operating hub 45 whereby the pinion may be manually rotated. To protect the pinion 43, the holder

35 for the sleeve 36 may be formed with a housing 46 within which the pinion is journaled.

The mold C may be of any desired type, and as here shown has a depression 47 made 70 in the top face of the plaster of Paris or other appropriate investment 48, which depression communicates at 49 with the cavity 50 formed by inserting into the investment 48 the usual wax or other impression 75 from which the inlay casting is patterned. Mounted at opposite sides near the bottom of the depression 47 are carbon elements 51 which coöperate with the movable negative element 36¹ to produce the electric arc. 80 The carbon pencil 36¹ which constitutes the negative element and the carbon elements 51—51 are respectively connected to corresponding poles in suitable power circuit.

The operation is as follows:

The cavity 50 of the investment 48 having been modeled by the wax or other pattern, and the gold or other metal to be fused having been placed in the depression 47, the fusing is effected by swinging the arm 34 on its pivot to bring the negative element 36¹ which has been properly adjusted to give the proper heat intensity, against the carbon elements 51—51 (see Fig. 1). In this movement of the arm 34, the spring 32 is put 95 under tension. When the inlay has been fused the handle 17 of the frame 16 is grasped and the frame swung down to first automatically release the locking mechanism for the movable element 36¹. The cam shaft 100 end of the frame 16 pushes down on the rod 21 rocking the lever 22 and thrusting up on the rod 24. This lifts the latch 26 which is pivoted in the arm 34 out of engagement with the notch formed on the upper part of 105 the support 29 to which the arm 26 is pivoted. This permits the spring 32 which has been compressed in swinging the arm 34 forward to expand and thus return the arm 34 to normal position, and to subsequently 110 position the compressed air delivery E over the mold C, as shown in Fig. 2, and in such positioning automatically opening the bore 8 to permit the air to pass therethrough into the depression 47 and force the fused charge 115 through passage 49 into the cavity 50 formed in the investment 48. Specifically when the frame 16 is brought down, the inclined walls of the notch 20 force the rod 21 downwardly, rocking the lever 22 on its pivot 23 and raising the rod 24 thereby lifting the dog 26 sufficiently to cause its notch 31 to clear the support 29, whereupon the spring 32 turns the arm 34 on its pivot 33 until said arm rests upon the rigid underneath support provided for it by the extension 37. As will be evident, therefore, the movable element 36¹ is returned automatically and the operative is thus relieved of the trouble and 120 delay in handling these parts.

When the head 12 of the stem 7 contacts the investment 48, the continued downward pressure applied to the stem by the handle 17, will cause said stem to move down into 5 the sleeve 11 a distance sufficient to carry the valve 10 away from its seat, thus opening the bore 8, such downward movement being resisted by the spring 7¹ which is thus compressed so that when the stem 7 is raised 10 by the lifting of the frame 16, said spring will hold down the sleeve 11 until the valve 10 again finds its seat, thus again sealing the bore 8.

The air supply is therefore automatically 15 opened and closed by and in the movement of the stem 7 to position, and the operative consequently relieved of the necessity of manually manipulating any controls for the air supply.

20 While I have shown and described my invention as operating with compressed air, it will be understood that I may use any other gaseous or vaporous agent which when released over the mold will exert sufficient 25 pressure to force the fused inlay into the pattern cavity.

While the device in the form shown is particularly adapted for use in dental work and is described with special reference to 30 such it is obvious that my invention is applicable to any small casting work as in the jewelers' trade in either manufacturing or repairing.

Various modification in the form and construction of my device may obviously be resorted to if within the limits of the appended claims.

What I therefore claim and desire to secure by Letters Patent is:

40 1. In a casting machine, in combination, a mold, a movable pressure delivery having an effective and an ineffective position relative to said mold, a pivoted frame carrying said delivery, a pivoted electrical heating 45 element having an effective and an ineffective position relative to said mold according to the position of said delivery, a latch for locking said heating element in effective position and released by the movement of the 50 delivery to effective position, a spring for moving said heating element to ineffective position upon release of said latch, and an operative connection from said frame to said latch for releasing said latch upon a 55 movement of the delivery to effective position to permit said spring to move the heating unit to ineffective position.

2. In a casting machine, in combination, a

mold, and a movable heating unit including a rigid support, an arm mounted to turn on 60 said support, a spring for turning said arm, a latch controlling said spring, a release for said latch to permit said spring to turn said arm to ineffective position, and a heating element mounted on said arm.

3. In a casting machine, in combination, a mold, a pressure delivery having an effective and an ineffective position relative to said mold, a movable heating unit including a rigid support, an arm mounted to turn on 70 said support, a spring for turning said arm to its ineffective position, a latch controlling said spring, a release for said latch operated by said pressure delivery in its movement to effective position to release said spring and 75 allow it to turn said arm to ineffective position, and a heating element mounted on said arm.

4. In a casting machine, in combination, a mold, a stationary carbon element associated 80 therewith, a movable carbon element adapted to coöperate with said stationary element, and a support for said movable element including an arm turnably mounted, a sleeve carried by said arm for holding said movable carbon element, and means for adjusting said carbon element independently of the movement of said arm.

5. In a casting machine, in combination, a mold, a stationary carbon element associated 90 therewith, a movable carbon element adapted to coöperate with said stationary element, and a support for said movable element including an arm turnably mounted, a spring for turning said arm in one direction, and 95 an automatic release mechanism for said spring.

6. In a casting machine, in combination, a mold, a stationary carbon element associated 100 therewith, a movable carbon element adapted to coöperate with said stationary element, and a support for said movable element including an arm turnably mounted, a sleeve carried by said arm for holding said movable carbon element, rack teeth on said 105 sleeve, and a pinion carried by said arm and meshing with said rack teeth for adjusting said carbon element independently of the movement of said arm.

In testimony whereof I affix my signature 110 in presence of two witnesses.

HORACIO MIRA.
